UNITED STATES PATENT OFFICE.

JOHN E. WARD, OF NEW YORK, N. Y., ASSIGNOR TO STANDARD HEAT AND VENTILATION COMPANY, INC., A CORPORATION OF NEW YORK.

CAR-VENTILATOR.

1,092,879.

Specification of Letters Patent. Patented Apr. 14, 1914.

Application filed September 7, 1912. Serial No. 719,087.

To all whom it may concern:

Be it known that I, JOHN E. WARD, a citizen of the United States of America, residing in the borough of Manhattan, in the city, 5 county, and State of New York, have invented certain new and useful Improvements in Car-Ventilators, of which the following is a specification.

The invention relates to car ventilators.

10 One of the objects of the invention is to provide a car ventilator which can be placed on the roof of a car so as to exhaust the air from the upper interior portion of the latter.

15 Another object of the invention is to construct a ventilator which will be simple and efficient and also neat in appearance when on the car.

20 As showing a specific embodiment of the invention, reference is made to the drawing forming a part of this specification and in which—

25 Figure 1 shows the end view of an upper portion of a car with the ventilator applied thereto. Fig. 2 shows a partial side view of the upper portion of a car with a ventilator in place thereupon. Fig. 3 is a partial side view and a partial longitudinal sectional view of the ventilator. Fig. 4 is a partial 30 end view and a partial transverse vertical sectional view of the ventilator. Fig. 5 is a view looking upwardly toward the under side of the ventilator. Fig. 6 is a plan view of the ventilator, and Fig. 7 is a view taken 35 on the line 7—7 of Fig. 4 looking in the direction of the arrows. Figs. 5, 6 and 7 are all shown at a smaller scale than Figs. 3 and 4 and it will be observed that Fig. 3 is a view taken on the line 3—3—3—3, looking 40 in the direction of the arrows $x-x$ shown in Fig. 6, and that Fig. 4 is a view taken on the line 4—4—3—4 looking in the direction of the arrows $y-y$ shown in said Fig. 6.

45 The ventilator comprises the upright throat or air intake portion 1, the roof portion 2 and the air deflecting or suction creating portions 3, 4, 5 and 6. The upright throat portion is hexagonal in cross section and is 50 defined by the upright sides 7 and 8 and the

end portions 9, 10, 11 and 12. The upright side and end portions of the throat have thereupon flanges 13 which provide means whereby the ventilator may be secured in place on the car. The roof is located over 55 the throat portion and extends on opposite sides thereof. The roof is preferably substantially lozenge shaped in plan view and preferably transversely arched so that it slopes downwardly from the longitudinal 60 center toward the sides.

The deflecting portions 3 and 4 are located at one end of the ventilator and the deflecting portions 5 and 6 are located at the other end of the ventilator, and it will 65 be noted that they extend downwardly from the roof to the throat portion and outwardly from the ends of the ventilator toward the central portion thereof. From an inspection of the drawings it will be observed that 70 the surface elements, in these deflecting portions, which are in a horizontal plane diverge in passing from the end of the ventilator toward the central portion of the sides, and that the surface elements, in said 75 deflecting portions, which lie in a vertical plane approach each other in passing from the roof toward the throat portion.

The side edge 2^a of the roof, the deflecting portion 5, the upright side 8 of the 80 throat and the deflecting portion 4 define the air delivery opening A at one side of the ventilator, and the side edge 2^b, the deflecting portion 3, the upright side 7 of the 85 throat portion and the deflecting portion 6 define the air delivery opening B at the other side of the ventilator. Both of these delivery openings A and B are open from the bottom. Each of the deflecting portions is provided with a depending flange (see 3^a of Fig. 3; 4^a and 6^a of Fig. 4). Due to the 90 deflecting portions and the depending flange portions a suction will be created when the ventilator is moved in a longitudinal direction, and therefore these deflecting portions 95 and the flanges thereof provide a means for sucking the air from the interior of the car through the throat and causing it to be delivered through the air discharge openings A and B.

It will be observed that the side sections of the ventilator which are on opposite sides of the centrally located and vertically and longitudinally extending plane M—M are symmetrical, and that the end sections on opposite sides of the vertically and transversely extending plane L—L are also symmetrical.

The improvements herein set forth are not limited to the precise construction and arrangement shown and described and they may be embodied in various forms and modifications without departing from the spirit and scope of the invention.

15. What I claim is:

1. A ventilator for cars having the side sections on opposite sides of a centrally located vertically and longitudinally extending plane symmetrical and having the end sections on opposite sides of a vertical and transversely extending plane also symmetrical, said ventilator having an intake opening at the bottom, an upright throat portion which is hexagonal in cross section, a substantially lozenge shaped roof transversely arched and end portions having outer surfaces whose surface elements which lie in a horizontal plane extend outwardly in passing from the end of the ventilator toward the centrally located transverse plane above referred to, and whose surface elements which lie in a vertical plane approach each other in a downwardly direction, the roof, ends and sides of the vertically extending throat portion forming the air suction and delivering means and defining the air delivering openings which are open from below and which are located at the under sides of the ventilator on opposite sides of the longitudinally and vertically extending central plane above referred to.

2. A ventilator for railway cars having a throat portion providing an intake opening at the lower central portion of the ventilator, a roof which extends over the throat portion on opposite sides thereof, and two portions at each end of the ventilator, said portions having surfaces that diverge in passing from the end of the ventilator toward the central portion of the ventilator and which converge in passing from the roof of the ventilator toward the bottom portion thereof, said deflecting portions having therebetween the air delivery means of the ventilator which terminates in the air delivery opening at the under side of the ventilator.

3. In a ventilator for railway cars the combination of a vertically extending throat hexagonal in cross section, securing flanges thereupon, a substantially lozenge shaped roof and walls or portions which extend inwardly and downwardly from the roof to the throat portion and outwardly in pass-

ing from the end of the ventilator toward the central portion thereof, said deflecting portion at each side of the ventilator having therebetween the air delivery opening.

4. In a ventilator for railway cars the combination of a vertically extending throat hexagonal in cross section, securing flanges thereupon, a substantially lozenge shaped roof and walls or portions which extend inwardly and downwardly from the roof to the throat portion and outwardly in passing from the end of the ventilator toward the central portion thereof, said deflecting portion at each side of the ventilator having therebetween the air delivery opening, said deflecting portions at each side of the ventilator being provided with depending lips or flanges.

5. A ventilator for railway cars having an intake or throat portion located centrally and at the lower side thereof, a roof portion and deflecting portions at each end of the ventilator which diverge passing toward the central portion and which converge passing toward the bottom portion, said deflecting portions on opposite sides of a vertically and horizontally extending central plane passing through the ventilator being symmetrically arranged and the deflecting portions at each side of the ventilator providing a part of the air suction and delivering means.

6. In a car ventilator the combination of a longitudinally extending and transversely arched roof, deflecting portions at opposite ends of the ventilator, which deflecting portions approach the sides of the ventilator in passing from the end thereof toward the central portion of the ventilator and which also approach each other in passing from the top of the ventilator toward the base thereof and an upright throat portion, the side edges of the roof, the adjacent ends of the deflecting portions and the side portions of the throat defining the air delivery openings which are located at the under side of the ventilator.

7. A ventilator for railway cars having an intake portion located centrally and at the lower side of the ventilator, a roof portion above the same and extending on opposite sides of the intake portion, and deflecting portions on each of the opposite ends of the ventilator, which deflecting portions diverge outwardly in passing from the end of the ventilator toward the central portion thereof, the ventilator being provided with air discharge openings on each side thereof, which said discharge openings are located between the adjacent deflecting side portions at the side of the ventilator.

8. A car ventilator comprising a throat portion at the lower side thereof, a roof portion thereover extending on opposite

sides thereof, and deflecting portions at each end of the ventilator, said deflecting portions approaching each other in passing downwardly from the roof, said 5 ventilator being provided with air discharge portions at opposite sides thereof which are open from below.

This specification signed and witnessed this 5th day of September A. D. 1912.
